UNITED STATES PATENT OFFICE

PAUL E. HARTMANN, OF HILLSIDE TOWNSHIP, UNION COUNTY, NEW JERSEY, AS
SIGNOR TO J. E. MERGOTT COMPANY, OF NEWARK, NEW JERSEY, A CORPORATION OF
DELAWARE

HAND BAG

Application filed February 15, 1932. Serial No. 592,934.

This invention relates to hand bags, and more particularly to means for effectively securing bag covering material to metal frames used in hand bags.

Heretofore, it has been the custom to secure bag covering material directly to frame members by sewing, riveting and similar means. But such expedients have been found objectionable in that they are in some cases expensive, and, in other cases, inconvenient, and result in an unsightly hand bag. Inasmuch as the merchandising of hand bags is highly competitive, it is imperative that such bags be manufactured as economically as practicable without lowering the standard of quality or affecting the appearance of the finished article.

It is an object of this invention to provide inexpensive means for conveniently and effectively securing covering material to hand bag frame members without in any way affecting the standard of quality.

A further object is the provision of an inlay, substantially U-shaped, to which the hand bag covering material is secured, which can be readily secured to a hand bag frame member by simple clinching means.

A further object is the provision of an inlay having a plurality of spaced tabs along an edge thereof, each tab having an apertured protuberance and being bendable parallel to the inlay, the latter having spaced apertures registering with the protuberances, said protuberances and apertures cooperating to enable bag covering material to be expeditiously and conveniently secured to the inlay before the latter is attached to a bag frame member.

A further object is the provision of an inlay adapted to be secured to a hand bag frame member, said inlay having means to enable bag covering material to be secured thereto, before the inlay is secured to the bag frame member.

At present, the majority of hand bag frame members are of the channel type in which the bag covering material is clinched to the frame members by pressing the walls of the channels together. However, such an expedient for attaching covering material to a frame mem-

ber is objectionable in that the clinching of the walls causes the inner and adjacent side walls of the two hinged members of a bag frame to be distorted and unsightly in appearance, and the distortion and irregularity of the inner adjacent side walls makes the action of latching means uncertain.

It is, therefore, an object of this invention to provide inlays to which the bag covering material can be attached independently of the bag frame members, after which the inlay can be secured to the frame member without danger of distorting and affecting the smooth, even, surface of the adjacent side walls of the hinged frame members.

One of the problems heretofore encountered in attaching bag covering material to bag frame members has been the compensating for the bunching of the material at the corners of the frame members. It is a further object of this invention to provide an inlay having means for facilitating the attaching of bag material to the corners thereof in a flat and neat manner without bunching, the bag covering material being entirely attached to the inlay before the latter is secured to a frame member.

These and other objects are attained by the novel construction, combination and arrangements of parts hereinafter described and shown in the accompanying drawing, constituting a material part of this disclosure, and in which:

Fig. 1 represents a perspective view of a hand bag embodying my invention.

Fig. 2 represents a perspective view of an inlay embraced by my invention.

Fig. 3 represents a perspective view showing a channelled frame member in position to receive an inlay.

Figs. 4 and 5 show the manner in which bag covering material is secured to an inlay, and the latter inserted in a channelled frame member.

Fig. 6 shows an inlay with bag covering material attached thereto, securely clamped in the channel of a frame member, and

Fig. 7 shows the manner of attaching the bag covering material to the corners of an inlay.

Referring to the drawing, in Fig. 1 is shown a hand bag having a pair of similar channelled U-shaped frame members 8 and 9, hingedly connected. Each frame member is made from a suitable blank of material bent to present, in cross-section, an outwardly disposed channel having an inner side wall 10 provided with a top flange 11, and a bottom flange 12, which is of less width than the top flange 11, said flanges being directed outwardly at right angles to the side wall 10. The bottom flange 12 has a plurality of tabs 13 adapted to be bent towards flange 11 for the purpose hereinafter described, and the flange 12 is provided with perforations 14 adjacent the tabs to facilitate the bending of the latter.

In Fig. 2 is shown an inlay 15, which is made from a sheet of material and shaped to conform with the shape of the frame member into which the inlay is inserted. In the present case, the frame member is U-shaped, and, accordingly, the inlay is of the same shape. The inlay is provided, along its inner edge, with spaced tabs 16. Each tab 16 has a portion punched through to provide an apertured protuberance 17, which, when the tabs 16 are bent up towards the outer edge of the inlay as shown in Figs. 2 and 4, register with and enter apertures 18 in the inlay 15. At the corners the inlay 15 is punched out to provide tabs 19 to facilitate securing bag covering material to the corners of the inlay as herein-after described.

In practice, the bag covering material 20 is secured to inlay 15, see Figs. 3, 4 and 5, by bending the tabs 16 upwardly and pressing them against the body of the inlay, to cause the protuberances 17 to force the material into the apertures 18, see Fig. 5. The material 20 is then folded over the upper edge of the inlay 15, so that the main portion of the material lies on the side of the inlay opposite to the side carrying the tabs 16.

At the corners of the inlay 15, the section 21 of the material is clinched securely by the tab 19, after which section 22 of the material is folded over tab 19 and secured to the leg 23 of the inlay by a tab 16, see Fig. 7.

After the covering material has been attached to the inlay 15 as above described, the inlay is inserted in the channelled frame member, and the tabs 13 bent up to securely clinch the inlay in the frame member, see Figs. 4, 5 and 6.

From the above description it will be seen that I have provided an inexpensive and simple expedient for attaching bag covering material to hand bag frames. By using the inlay, the bag covering material may be entirely attached thereto before the inlay is inserted in the frame member, and due to the shape and nature of the inlay the attaching of the covering material thereto may be conveniently and neatly performed, so that when

the inlay is finally inserted in the frame member, and securely clinched in position by the tabs 13, the inlay is completely concealed by the bag covering material and the upper flange of the frame member. The hand bag has a neat and finished appearance with no means for attaching the covering material to the frame members being in evidence.

The foregoing disclosure is to be regarded as descriptive and illustrative only, and not as restrictive or limitative of the invention, of which, obviously, an embodiment may be constructed including modifications without departing from the general scope herein described and denoted in the appended claims.

Having thus described my invention, what I claim as new and desire to secure by Letters Patent, is:

1. In a hand bag, a frame member having an inner side wall provided with top and bottom flanges, an inlay having substantially the same shape as the frame members, means on the inlay for attaching bag covering material thereto, and spaced tabs integral with the bottom flange, said tabs being adapted to be bent up to clinch the inlay in the frame member between the top and bottom flanges.

2. In a hand bag, a substantially U-shaped inlay having a plurality of spaced tabs along its inner edge, each tab having an apertured protuberance, said tabs being bendable upwardly parallel with the inlay, said inlay having spaced apertures registering with the protuberances when the tabs are bent upwardly.

3. In a hand bag, an inlay having a plurality of spaced tabs along one of its edges, each tab having a protuberance, said inlay having a plurality of spaced apertures, said tabs being bendable parallel to the inlay to cause the protuberances to register with the apertures.

This specification signed this 13th day of February, 1932.

PAUL E. HARTMANN.
